UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

CREASING MECHANISM FOR SHEET COLLECTING AND FOLDING MACHINES.

1,243,684.

Specification of Letters Patent. Patented Oct. 23, 1917.

Application filed December 19, 1914. Serial No. 878,153.

To all whom it may concern:

Be it known that I, HOWARD M. BARBER, a citizen of the United States, and resident of Stonington, in the county of New London and State of Connecticut, have invented 5 a new and useful Improvement in Creasing Mechanism for Sheet Collecting and Folding Machines, of which the following is a specification.

10 The object of my invention is to provide means for creasing partially folded signatures so that when the signatures are finally folded, cut, gathered and secured together, the product thus formed will readily lie 15 open at any particular page.

A further object is to provide means for creasing a transversely folded signature longitudinally of its travel upon one or both sides of its longitudinal fold line before 20 its longitudinal fold is made.

25 A still further object is to provide means for reversely creasing the partially folded signature upon one or both sides of the longitudinal fold line so that the leaves will readily fold back either way along the creases thus formed.

A practical embodiment of the invention is represented in the accompanying drawings, in which,

30 Figure 1 is a view in side elevation of so much of a sheet collecting and folding machine as includes my invention.

Fig. 2 is a vertical section taken within and adjacent to the near side frame of the 35 machine.

Fig. 3 is a partially inverted plan view showing the creasing mechanism.

Fig. 4 is a vertical section taken just inside the far side frame.

40 Fig. 5 is a detail diagrammatic section taken centrally through the machine from front to rear.

Fig. 6 is an enlarged diagram showing the result of the first set of creasing rolls, 45 and

Fig. 7 is a similar view showing the result of the second set of creasing rolls.

The two side frames of the machine are denoted by 1 and 2. The web feed mechanism is denoted by 3. The pair of rotary cutters 4, 5 have shafts 6, 7, which cutters are, in the present instance, shown as provided with one set of coacting blades 8, 9, arranged to cut the web transversely into 55 one sheet for each revolution of the cutters.

The sheet collecting cylinder 10 has a shaft 11, which cylinder is herein shown as provided with one set of grippers 12. This collecting cylinder 10 also acts as a folding-off cylinder and it is provided with 60 a tucking blade 13 arranged to coact in the present instance, every two revolutions of the collecting cylinder 10 with the folding jaws 14 carried by the female folding cylinder 15, the shaft of which is denoted by 16. 65 This folding mechanism imparts a fold to the signature transversely to its travel. The folding mechanism herein shown on the cylinders 10 and 15 is of the well known floating folding blade and jaw type, and the 70 cylinder 15 is shown as making one revolution to two revolutions of the collecting cylinder 10.

A cylinder 17 is mounted on a shaft 18, which cylinder in the present instance, 75 serves as a slitting cylinder and as a first creasing cylinder. This cylinder is provided with a set of grippers 19 arranged to receive the first folded signature from the cylinder 15 and transfer the same to the 80 grippers 20 on the cylinder 21, the shaft of which is denoted by 22. The grippers 20 are arranged to transfer the transversely folded signature to the grippers 23 on the delivery cylinder 24, the shaft of which is 85 denoted by 25. This cylinder 24 is arranged to deliver the sheet on to the folding table 26 by any suitable means, such as the two sets of endless tape carriers 27, 28. On this table 26, the transversely folded signature 90 is folded longitudinally of its travel by the usual folding blade 29 and coacting jaws 30.

The cam mechanisms for insuring the proper opening and closing of the grippers on the cylinders 10, 15, 17, and 24; the cam mechanism for insuring the folding off of the collected sheets from the cylinder 10 to the cylinder 15, and for controlling the floating of the tucking blade and folding jaws, and the mechanism, not shown, for controlling the operation of the folding mechanism for imparting the longitudinal fold to the transversely folded signature, will not be specifically described herein as they may be of any well known or approved form and are not a part of the present invention, which invention is directed to the creasing of the partially folded signatures, the mechanism for which will now be described.

The cylinder 21, as shown, is one-half the 110

size of the cylinders 17 and 24, and travels at the same surface speed thereof. Therefore, the grippers 20 are operated every second revolution of the cylinder 21, both to take the advance edge of the transversely folded signature from the grippers 19 and to transfer the advance edge of the signature to the grippers 23. This is accomplished by a rocking cam arm 57, carrying the cams 58, 29, which arm is controlled by a box cam 60 on the shaft 25 of the cylinder 24, through the connecting rod 61 and rocking arm 62.

First creasing disks 31, 32, 33, are shown as coacting with the cylinder 17, the disk 31 being arranged to crease the transversely folded signature longitudinally of its travel along its longitudinal fold line so as to facilitate the folding of the said signature longitudinally of its travel on the table 26. The creasing disks 32, 33, are arranged to coact with the cylinder 17 to produce the first creases longitudinally of the travel of the transversely folded signature upon the sides of and parallel with the longitudinal fold line and at predetermined distances therefrom. Second creasing disks 34, 35 are arranged to coact with the cylinder 21 to reversely crease the transversely folded signature longitudinally of its travel along the first creases formed by the creasing disks 32, 33. The creasing disk 31 is supported from a crossbar 36. The creasing disks 32, 33 are supported from the crossbar 37, and the creasing disks 34, 35 are supported from a crossbar 38.

If so desired, the transversely folded signature may be slit longitudinally of its travel into any number of smaller signatures by one or more slitting disks 39, supported from the crossbar 36, it being understood that the sets of creasing disks correspond in number to the number of smaller signatures which are slit from the transversely folded signature by said slitting disk or disks 39. In the present instance, I have shown one of these slitting disks 39 mounted on a cross shaft 40, and I have shown two sets of creasing disks, the disk 31 being mounted on a cross shaft 41, and the disks 32, 33, 34, 35, being mounted on cross shafts 42, 43, 44, 45 respectively.

The several rotary parts are interconnected to move at the desired relative speeds through a train of gearing 47, 48, 49, 50, 51, 52, 53, 54, 55, 56.

I wish it understood that by the term "cylinder" I contemplate any suitable means for carrying the sheets through the prescribed paths, and by the term "grippers" I contemplate any suitable means for engaging said sheets.

In the embodiment of the invention shown and described herein, the operation of the machine is as follows: The web as it comes

from the press is cut transversely into sheets and two sheets are collected on the cylinder 10 and then folded off to the cylinder 15. The cylinder transfers the transversely folded signature to the cylinder 17 where the signature is slit longitudinally of its travel into a plurality of smaller signatures, and each of these smaller signatures is provided with the first longitudinal creases, one along the longitudinal fold line and the others upon opposite sides thereof. Each transversely folded signature is then transferred to the cylinder 21 where the creases upon opposite sides of the longitudinal fold line are reversely creased. The thus creased signatures are then transferred to the cylinder 24, and delivered on to the folding table 26, where each signature is folded longitudinally of its travel along the crease between the two reverse creases.

This reverse creasing of the signature adjacent to its longitudinally folded edge and parallel therewith, will permit each of the leaves to be readily turned back and forth on the said reverse crease as a hinge, permitting the product formed from a signature or collected group of signatures to be readily opened and when open, to lie flat at any particular portion thereof.

It is evident that various changes may be resorted to in the construction, form and arrangement of the various parts without departing from the spirit and scope of my invention and hence I do not wish to limit myself strictly to the construction herein set forth, but

What I claim is:

1. In a machine of the character described, means for folding a signature longitudinally of its travel and means for creasing the signature in opposite directions along the same line in close proximity and parallel to the longitudinal fold line.

2. In a machine of the character described, means for folding a signature longitudinally of its travel and means for creasing the signature in opposite directions along the same lines upon both sides of, parallel, and in close proximity to the longitudinal fold line.

3. In a machine of the character described, means for folding a signature transversely and longitudinally of its travel and means for creasing the signature in opposite directions along the same line in close proximity and parallel to its longitudinal fold line.

4. In a machine of the character described, means for folding a signature transversely and longitudinally of its travel and means for creasing the signature in opposite directions along the same lines upon both sides of, parallel, and in close proximity to its longitudinal fold line.

5. In a machine of the character de-

scribed, means for folding a signature transversely and longitudinally of its travel and means for creasing the signature in opposite directions along the same line upon one 5 side of, parallel and in close proximity to its longitudinal fold line before the longitudinal fold is imparted to the signature.

6. In a machine of the character described, means for folding a signature transversely and longitudinally of its travel and 10 means for creasing the signature in opposite directions along the same lines upon both sides of, parallel and in close proximity to its longitudinal fold line before the longitudinal fold is imparted to the signature.

7. In a machine of the character described, means for imparting a plurality of folds to a signature, carriers for the folded 15 signatures and means coacting with the carriers for reversely creasing the signature.

20 8. In a machine of the character de-

scribed, means for folding a signature transversely of its travel, carriers for the transversely folded signature and means coacting with the carriers for reversely creasing the 25 signature longitudinally of its travel.

9. In a machine of the character described, means for folding a signature transversely of its travel, carriers for the transversely folded signature, means coacting 30 with the carriers for reversely creasing the signature longitudinally of its travel and means for folding the signature longitudinally of its travel.

In testimony that I claim the foregoing 35 as my invention, I have signed my name in presence of two witnesses, this fourteenth day of December, A. D. 1914.

HOWARD M. BARBER.
